UNITED STATES PATENT OFFICE.

WILLIAM C. TERRY AND CHARLES JOERIGHT, OF CHAGRIN FALLS, OHIO.

SPRING-WHEEL.

1,187,203.

Specification of Letters Patent. Patented June 13, 1916.

Application filed December 8, 1915. Serial No. 65,839.

To all whom it may concern:

Be it known that we, WILLIAM C. TERRY and CHARLES JOERIGHT, citizens of the United States, residing at Chagrin Falls, in the county of Cuyahoga and State of Ohio, have invented new and useful Improvements in Spring-Wheels, of which the following is a specification.

The present invention relates to the construction and arrangement of a wheel and more particularly to an improved type of rim therefor in which the shocks incident to travel are absorbed by means of springs in place of the usual pneumatic cushion of the inflated type of tire.

A further object of the invention is the provision of a device of the above stated character wherein by providing a plurality of springs eliminates the bringing of excessive pressure on one single spring, and further provides tractive engagement between the outer and inner rim sections of the wheel through the medium of such springs, the outermost terminal of each spring carrying friction rollers operating in tracks provided by the outermost section of the rim, whereby when a rough road is encountered the outer rim section will be forced toward the inner rim section and in so forcing compresses the spring with the result that the springs act to absorb the shock.

A still further object of the invention is the provision of mud guards fixedly secured to the outermost section of the rim and housing the springs to shield the same from dust, dirt and the like.

With the above and other objects in view, the invention consists in the novel features, details of construction, and combination of parts which hereinafter will be more fully set forth, illustrated in the accompanying drawing and pointed out in the appended claims.

Figure 1 is a fragmentary side elevation; Fig. 2 is a longitudinal section; Fig. 3 is a transverse section; and Fig. 4 is a detail view of one of the springs employed.

Referring to the drawings by characters of reference, the numeral 5 represents the hub of a wheel from which radiate a series of spokes 6, of wood, metal or other suitable material having their inner ends rigidly supported within the hub, while their outer ends have secured thereto in any preferred manner the felly 7. We employ in connection with the wheel of the above stated

character, an improved rim which comprises a solid annular inner ring 8 which may be constructed of metal or other suitable material and is fixedly secured to the felly 7 by means of bolts 9 and is arranged concentric to the felly 7. The improved type of rim further constitutes an outer ring 10 of a diameter larger than the diameter of the inner ring 8 and is arranged in spaced concentric relation therewith. The said outer ring is constructed of a pair of upper and lower L-shaped sections 11 and 12 respectively and secured to one another by means of transverse bolts 13. Each of the L-shaped sections constituting the outermost ring 10

is provided on one of its edges with an upstanding annular flange 14 forming within the outermost ring a pair of annular tracks 15 and 16 respectively. A plurality of curved leaf springs 17 are interposed between the inner and outer rings 8 and 10 respectively to furnish the proper resiliency to the wheel. The inner ends of the springs are arranged in overlapped relation one to the other as indicated at 18 and riveted in the annular groove 19 of the inner ring 8, by means of fasteners 20. The opposite ends of the springs 17 or the free ends thereof, are formed with substantially vertically disposed thickened end portions 21 which protrude through the slots 22 of the lowermost L-shaped section 12 of the outer ring 10. The slots 22 are disposed in a spaced circumferential series throughout the entire circumference of the lower L-shaped section 12 and are of a width lesser than the space 23 formed between the upper and lower L-shaped sections to provide the tracks 15 and 16 with a horizontally disposed portion 24

which serves as a bearing for the friction rollers 25 and 26 carried upon the extending portions 27 of the stop pins 28. The pins 28 are detachably mounted in the loops 29 formed on the terminal portions of the thickened end portions 21 of each of the springs 17.

It will be obvious from inspection of the drawing that when a rough road is encountered the outer rim section will be forced toward the inner rim section and in so forcing move the free ends of the springs longitudinally in the slots 22 and the free movement of the springs within the slots is caused by the travel of the friction rollers against the opposed inner solid portions of the respective upper and lower L-shaped sections

- of the outer rim 10, and in the tracks 15 and 16 respectively and in so doing will force or compress the springs with the result that the springs will act to absorb the shock. Bolts 5 30 pass transversely through the outer ring 10 for connecting therewith mud guards 31, which in this instance are shown as constituting a pair of metallic rings 32 having their lower portions terminating substantially 10 flush with the inner circumference of the inner ring 8 and shield the leaf springs 17 from dust, dirt or the like, while the opposite ends 33 of the mud guards 31 project above the plane of the outer ring 10 to provide 15 the latter with a groove for holding a solid rubber tire 34.

From the foregoing description, taken in connection with the accompanying drawing, the advantages of construction and of the 20 method of operation will be readily apparent to those skilled in the art to which the invention relates, and while we have described the principles of operation of the device together with the device which we 25 now consider to be the best embodiment thereof, we desire to have it understood that the device shown is merely illustrative and that such changes may be made when desired as are within the scope of the claims 30 appended thereto.

We claim:

1. In a spring wheel, a hub, a felly connected to said hub by means of spokes, a rim secured to said felly comprising a solid inner 35 ring and a sectional outer ring, the sectional outer ring being disposed in spaced circumferential relation to the inner ring, a plurality of leaf springs interposed between the spaces of the rings and having their inner 40 ends fixedly secured to the outer periphery of the innermost ring, the opposite ends of the springs being provided with upstanding thickened portions terminating in loops, and a series of friction rollers supported in 45 the loops of said springs and operating upon the opposed surfaces of the sections of the outermost ring.
2. In a device of the class described embodying a rim consisting of a solid inner 50 ring and a sectional outer ring, the sectional

outer ring being disposed in spaced concentric relation with the solid inner ring and formed with a series of slots, means for securing the sections of the outer rings together, a plurality of springs interposed between the inner and outer rings and having their inner ends fixedly secured to the outer periphery of the inner solid ring, the opposite ends of the springs protruding through the slots of the outermost ring and terminating in looped ends, pins mounted in the looped ends of said springs and projecting beyond the ends thereof, and a series of anti-friction rollers mounted upon the projecting ends of said pins and operating upon the opposed surfaces of the sections of the outermost ring upon contraction of said springs.

3. In a spring wheel, a hub, a felly connected to said hub by means of spokes, a rim secured to said felly consisting of a solid inner ring and a sectional outer ring, the said sectional outer ring embodying inner and outer L-shaped sections and the inner L-shaped section having formed in its horizontal portion a series of concentrically arranged slots, the outer L-shaped section being disposed in spaced circumferential relation to the inner L-shaped ring section, means for securing the L-shaped sections of the outer ring together, a plurality of leaf 75 springs fixedly secured at their inner ends to the outer periphery of the inner ring section, the opposite ends of the springs protruding through the slots of the innermost L-shaped section of the sectional outer ring 80 and within the spaces between the said L-shaped sections, and friction rollers supported upon the free ends of the springs and operatively mounted between and on the opposed faces of the horizontal portion of 85 the said inner and outer ring, substantially as and for the purpose specified.

In testimony whereof we affix our signatures in presence of two witnesses.

WILLIAM C. TERRY.
CHARLES JOERIGHT.
